FURNACE

Charles B. Yoder, Brentwood, Mo., assignor, by direct and mesne assignments, to Radiant Boiler Corporation, New York, N. Y., a corporation of New York

Application January 17, 1925, Serial No. 3,100

6 Claims. (Cl. 122—235)

My invention relates to improvements in a furnace and the main object of the invention is to so construct a furnace that the expense of installation and operation of said furnace is reduced to the minimum. Heretofore the failure of fire brick when subjected to high temperature has been taken as a matter of course, another trouble of furnace operation to be borne, and an extra boiler or furnace frequently was provided to enable repairs to be made without delay when the brick lining had become burnt out.

The main function of a boiler is to generate or produce steam at the lowest cost and in the operation utilize all possible heat and it is an object of my invention to provide a water or steam cooled furnace lining which allows a much higher temperature to be used without injury to the fire brick lining. This object is obtained by using a fire brick having an aperture therethrough and through which a boiler tube is extended, the tube being connected into the boiler circulation system so that instead of burning out the expensive fire brick I use the lining as additional heating surface for the boiler. The tubes keep the walls in absolute alignment in any shape desired for the water or steam in the tubes keep the fire brick cool and by so doing the heat carried away goes to the boiler in the form of steam, thus increasing the boiler efficiency.

A further object is to provide a construction that allows free expansion of both fire brick and the steel tubing. In the present method of laying up fire brick where no provision is made for expansion the fire brick frequently fails due to the severe compressive strains set up when the brick get hot and expand, said strains often stressing the boiler room building frame work so that the steel becomes bent and dangerous. This objection is overcome in my invention by having the brick loosely secured to the tubes whereby the tubes are permitted to slide inside of the brick lining or the brick slide on the tubes.

A still further object is to provide a self contained boiler unit that is held in the proper shape by these tubes and in this way save the expense of any steel superstructure to support the boiler. By doing this I secure a more uniform expansion throughout the boiler and setting for it is obvious that if all parts have the same temperature or the variation is general, the boiler and setting will expand with a breathing action as the temperature rises or falls and therefore the strains will not be excessive and the lining will last much longer or for the life of the boiler.

A still further object is to provide a boiler and

setting that is supported at the central portion only by means of retained rollers that allow the necessary expansion in every way: instead of hanging the heavy boilers from steel superstructures near the roof of the boiler room. The drum itself when considered as a beam is well able to support the boiler so that in my invention I use the drum as a beam and by adding additional rows of boiler tubes at the sides, ends, top or bottom where needed I provide an excellent support for the fire brick walls, and by so doing provide a reinforced furnace wall which is water-cooled whereby the strength of steel reinforcing tubes is insured.

In the accompanying drawings—

Fig. 1 is a half longitudinal section and elevation of a powdered fuel fired boiler constructed in accordance with my invention.

Fig. 2 is half longitudinal section and elevation of the end view of a powdered fuel fired boiler.

Fig. 3 is a plan view of a powdered fuel fired boiler shown in Figs. 1 and 2.

Fig. 4 is a partial end elevation of the middle drums of a powdered fuel fired boiler enlarged to show the roller construction that allows expansion of the above boilers.

Fig. 5 is a partial sectional view taken on line 5—5 of Fig. 4.

Fig. 6 is a partial section of the lower part of the fire brick lining showing the bricks reversed every other row so that one tube is exposed to the direct action of the flames and the next insulated from the flames by fire brick so that the boiler circulation is positive one tube hot or the riser and the next cooler allowing circulation, as shown on 6—6 of Fig. 1.

Fig. 7 is a longitudinal sectional elevation showing another type of powdered fuel fired boiler.

Fig. 8 is a half section and elevation of the end of a powdered fuel fired fire box, the section is taken on line 8—8 of Fig. 7.

Fig. 9 is a sectional plan view broken away to show the detailed construction of the walls and corner headers as shown on line 9—9 of Fig. 7.

Fig. 10 is a longitudinal sectional elevation showing my invention as applied to the fire box of a stoker fired boiler water cooled.

Fig. 11 is a half elevation and half sectional elevation as shown on line 11—11 of Fig. 10.

Fig. 12 is a partial section of a flat arch over the fire of a boiler having the arch brick supported by a steam superheater.

Fig. 13 is a partial end elevation of a boiler equipped with a flat arch.

Fig. 14 is a detailed view of a block used on my invention shown in Figs. 2 and 12.

Fig. 15 is a front elevation of my retained U shaped brick.

5 Fig. 16 is an end view of my U shaped brick.

Fig. 17 is a sectional plan view of my U shaped brick taken on line 17—17 of Fig. 15.

Fig. 18 is a front elevation of my retained U shape brick showing a hanger attached to the 10 tube for supporting the tube and brick work on long walls.

Fig. 19 is an end elevation of the hanger only.

Referring, by numerals, to the drawings 10 designates the top original boiler drums as used 15 on boilers of this type, and 11 designates the lower original drums shown in the central part of Figs. 1 and 2. The mud drum 12 and the drums 10 and 11 are connected by tubes 13 which support 20 brick 14 and circulate the water between drums 10 and 11 thereby cooling brick 14, and provide the two end walls 15 between drums 10 and 11, thus retaining the heat within the boiler setting.

Extending downwardly from drums 11 are tubes 16 that connect into mud drums 12. 25 Loosely secured by clips 17 to tubes 16 are brick 14 forming the lower end walls between drum 11 and mud drum 12. Under drum 11 a space 18 is provided for expansion of end walls 15. Tubes 16 are bent to provide an arch 33 under drums 30 11 for the admission of the powdered fuel that is blown through pipes 19 that guides the fuel through the apertures 20 in arch 33. The fuel is ignited after coming into the fire box, the flames sweeping downwardly so that the water in tubes 35 16, 21, mud drum 12, and vertical header 35 is subjected to the heat of the flames which water in turn keeps the brick 14 below their dangerous temperature. The flames then sweep upwardly through boiler tubes 22 common to boilers of this 40 type.

Connecting lower drums 11 above end walls 34 are large tubes 24 having ends 25 closed. Connected to tubes 24 are small tubes 21 terminating in verticle drums or headers 35 which are connected into the ends of mud drums 12 so that the complete lower portion of the boiler setting is connected into the boiler circulatory system. All tubes are covered with fire brick or other suitable refractory material. Brick 14 are laid with one 50 course having slot 27 turned inwardly exposing the tube to the direct action of the flames and the adjoining rows have slot toward the outside thus interposing a thin wall to the flames as shown clearly in Fig. 6. This is done to insure proper boiler circulation for the tube exposed to the flames will be the hot or risers and the tubes protected by the fire brick will be the cooler or down comers thus the contained water will circulate.

60 Laid on the upper side of large tubes 24 are common fire brick forming wall 31 through which are openings 39 for cleaning or inspecting the boiler apparatus. Above walls 31 are walls 32 laid up with bricks as shown in Fig. 14 having 65 each a hole 38 therethrough and the tubes 37 being extended through walls 32 and into headers on each side, said tubes 37 being extended from steam header 38 into superheated steam header 39 as shown in Fig. 3. The steam header is connected by large radius bend 40 to boiler outlet 41 so that the steam collected in the upper boiler drums is led through the upper side walls 32 which are hot from the hot gases from the powdered fuel and in this way the walls are cooled 70 by the steam and the steam is superheated. The 75

superheater tubes are insulated by the brick so that their life is greatly prolonged. The superheated steam is then led to the power units through pipes 42.

Upper walls 15 where they enter drums 10 have 5 openings 43 formed by omitting brick 14 at this point so as to allow the smoke to escape to the smoke stack 44 through breeching 45 built in the form of a hollow wall of metal resting on bend 46 of tubes 13 and also supported by braces 47 10 attached to the upper part of drums 10. The upper part of breeching 45 has a pipe connection 48 connected to spiral tubes 49 located in the brick work of the stack. Only a portion of the spiral tube 49 is shown in the drawings, but this 15 tube will preferably extend to the top portion of the stack and thence to the water main or pump which forces the cold water up to the top of the stack and down through the stack into the hot breeching and from the lower part of the breeching to the mud drum 12. The water passing through the spiral tube 49 is the feed water for the boiler and said feed water would be forced into the coldest part and then down through the hotter part of the stack thereby saving a part 25 of the heat that has been heretofore lost through the stack.

Stack is laid with brick similar to 14 having the tube 49 exposed to the hot gases, these tubes will become covered with soot and to keep these tubes 30 free from soot I provide an air pipe 50 extending upwardly in the center of the stack 44 having small pipes or nozzles 51 extending radially from air pipe 50.

Heretofore the boilers have usually been supported by structural steel superstructures on the outside of the settings and are hung from up near the roof of the boiler house thereby making it necessary to use vast quantities of steel in the construction of the boiler house so as to safely 35 carry this heavy load, and often confining the walls of the boiler setting between steel channels so that as the fire brick become hot and expand enormous loads are thrown onto these steel members or else the fire brick walls fail from crushing. 45 My invention overcomes these serious objections by allowing free expansion of the steel and fire brick, allowing the boiler to have a breathing action.

On the ends 52 of drums 11 are welded brackets 50 53 having grooves 54 formed thereon. The brackets 53 rest on rollers 55 that in turn rest in cradle 56, said cradle being provided with limiting grooves 57 formed on the underside thereof that coincide with rollers 58 resting on plate 59 55 which plate is attached to beam 60. The beam 60 is secured to columns 61 that are anchored into piers 62 below the boiler setting. The rollers as shown allow a free restricted movement as the boilers and setting expand in any way. This construction allows the lower part below the rollers to expand downwardly and the upper part to expand upwardly for at the top of breeching 45 a circular groove 26 is provided to hold sand 63. Extending downwardly from the base of stack 44 is a circular 65 metal casting that fits into the sand 63 thereby forming a simple sand seal to keep the smoke from escaping before going through the stack and also allows the upper part of boiler setting to expand upwardly. The stack is supported independently 70 from the building structure that supports casting 64, this building steel not shown.

Figures 7, 8, and 9 show my invention as applied to an inclined tube cross drum boiler having the front water leg 65 and rear water leg 66 made 75

wider so as to allow room for a row of tubes on each side of the boiler to support brick 61 that form the two upper side walls opposite the inclined tubes commonly used in boilers of this type.

5 Water leg 65 connects into the drum 63 having the bottom part resting on and connected into small drum 69. Connected into the bottom of drum 69 are small tubes 70, bent so as to form a flat arch 71 for the admission of the powdered fuel through 10 pipe 72. Tubes 70 terminate in small mud drum 73 and act as supports for front wall 74 which has the brick 14 secured loosely thereto as previously described. Brick 14 are reversed in this 15 wall having the tubes exposed to the flames at the top, and near the bottom where the ashes are likely to form the tubes are covered by reversing bricks 14 so as to be kept free from the ashes.

Mud drum 73 is connected to small rear drum 75 by bottom tubes 76 which are on the same angle as 20 the boiler tubes 77 so as to provide for an angled bottom of the fire box so that the ashes will slide down the bottom and thence out of the fire box through ash door 78 which is formed by omitting several of the bottom brick 79 when the bare tubes 25 are exposed forming a grate. Ends of walls 80 are large tubes 81 connected into ends 82 of drums 69, 75 and 73, having side wall tubes 83 expanded into same at the front and terminating in large tubes 84 forming the rear corners. Large tubes 84 connect 30 into the water leg 66 and the bottom end into rear drum 75 at the ends 85, as shown in Fig. 9.

Feed water passes through spiral tube 49 that is covered by brick 79 so as to keep the tubes clean 35 and free from soot so that the heat will penetrate the water in the tubes at a uniform temperature, thence through feed water pipe 86 and into mud drum 73.

In a boiler as shown on Figs. 7 and 8 every brick 40 in the boiler setting is cooled by the boiler water, all brick are confined in a pipe rack that supports the complete boiler setting thereby eliminating the necessity of using any structural steel, thus saving vast sums of money in the installation of 45 the boiler. As the complete setting has about the same temperature or a uniform temperature the expansion will be equal, and as this temperature never gets above the dangerous temperature of the fire brick, the expansion will be the minimum.

50 A further object of my invention is to provide an air cooled space 113 around the bottom part of the fire box so that should any of the furnace heat penetrate the brick walls above drums 73 and 75 the preheated air will be drawn into the furnace 55 through openings 114 and 115.

Wall 116 shown as a heavy line does not touch the brick work at any place and is preferably made of sheet steel so that should any expansion 60 take place as the temperature of this wall increases the wall will bulge slightly thus compensating for the expansion. Further this wall will keep any of the powdered fuel from escaping to the boiler room thereby causing an explosion for the finely ground coal is very explosive and care 65 should be taken in handling this dangerous material.

Figures 10 and 11 show my invention as applied to a stoker fired boiler and where it is desired to only cool and protect the brick work of the fire box over and around the stoker, indicated in outline in dotted line 86 in Fig. 10. The stoker is fed by coal through hopper 87 from spout 88. Over 70 stoker 86 near hopper 87 are brick 89 supported and cooled by tubes 90 which are connected into 75 large U shaped headers 91 shaped to conform to

the front end of fire box. Tubes 92 also terminate in these headers 91 and form a pipe rack for supporting the front wall fire brick having the tubes 92 exposed to the action of the flames.

The arch over the fire is also supported by tubes 5 93 that support brick 94 thus providing a flat arch which spreads the flames and thereby heats the boiler tubes, not shown, more uniformly. The tubes 93 terminate in a U shaped header 95 at the rear end of the fire box. The boiler feed 10 water is admitted through flanged pipe opening as shown in Fig. 11 and as this part of the boiler system is the lowest, the fire box pipe rack will always be full of water and as this water becomes hot the circulation will force it upward through 15 pipe 97 that is connected into the boiler proper.

Another important feature of my invention is that the complete fire box can be removed from under the boiler as a whole by simply disconnecting the feed water pipe connection and the discharge pipe connection that connects to the boiler, the complete fire box is then pulled from under the boiler and a new fire box similar to the old can then be put in place and the pipe connections made, when the boiler is again ready for 25 operation. This is important for it is more economical to provide a spare fire box than it is to provide a spare boiler as is now the common practice in boiler room operation.

A fire box as above described will last the life 30 of the boiler for it is impossible to heat the brick above their dangerous temperature. Instead of burning out the expensive fire brick and causing a serious loss due to the fact that the boiler is 35 shut down during repairs that are so often needed now I use the wall surfaces for additional heating surfaces toward the boilers final product; steam.

Another important feature of my invention is the simple shaped fire bricks used, for in the manufacturing of fire brick it is necessary to carry 40 a number of brick in stock and thereby avoid the delay of having to manufacture special shaped fire brick, when the customers need the fire brick for repairs.

In operating the present stoker fired boilers the 45 arch over the flames burns out very quickly, and the complete combustion of the fuel cannot be obtained for the usual fire brick arch fails when the boiler is forced to any great degree. My invention also permits forcing the boiler to the 50 utmost due to the cooling action of the feed water, without in any way interfering with the production of steam. Furthermore the strength of the steel tubes is in no way impaired by the heat due to the cooling action of the feed water for it 55 is impossible to get these tubes red hot.

Figs. 12 and 13 show my invention as applied to a flat arch over a fire box or furnace that requires a steam superheater and has no room for the usual type of steam superheater or the boiler 60 owner may desire to resuperheat the steam after it has performed a part of its function.

Boiler outlet pipe 98 broken away leads the boiler steam to steam header 99 which has smaller tubes 100 through arch brick 79 forming the arch 65 101. Thus the invention provides an insulated superheater over the hottest part of the furnace. The tubes 100 are connected into header 99 and superheated steam header 102 so that all steam from the boiler is circulated through the hot 70 brick work composing arch 101 thereby cooling the hot brick and steel tubes to below their dangerous temperature and in doing this the boiler steam temperature is greatly raised or superheated. The superheated steam header has a flanged con- 75

nection to which the necessary pipe is connected that leads the superheated steam to the power unit.

The most commonly used arches of the present day are built of wedge brick in the form of an arch and frequently fail by burning out or by crushing due to expansion strains set up when the confined arch gets hot so that it is imperative to allow for free expansion to obtain the best results. Fire brick will expand up to the temperature at which they are burned in the brick kilns and after this temperature has been exceeded they begin to shrink so that at some time after the fire is put under the arch the action of the arch changes from expansion to shrinkage. The tests performed by the Department of the Interior, Bureau of Mines as shown in their bulletin 223 clearly show that the temperature of the furnace changes inside of the furnace. That is along the walls the temperature is lower than it is in the central part of the furnace fire.

Undoubtedly the same conditions prevail inside of the brick kilns so that the temperatures at which these brick are burnt are in question, so that the boiler operator whose duty it is to ease up on the buck stays while the expansion is taking place must use judgment only when he has to begin tightening up the buck stays. This condition my invention overcomes, for set on the top of the furnace side walls 103 are T rails 104 that support the tubes 100. T rails 104 keep the arch brick forming arch 101 above the brick work forming the side walls so that the brick arch does not touch the side walls leaving an open space 105 which is filled with loose sand around the joints of the three sides so as to provide a tight furnace so that the heat cannot escape before performing its function.

A flat arch as above described provides for contraction or expansion, for the tubes are free to slide on the T rails with the minimum friction and should the brick expand more than the tubes they not being securely fastened to the tubes, slide on the tubes with the least friction. Should the complete arch expand in any way the loose sand will yield and still maintain a tight furnace. This provides a floating arch that is free to expand regardless of the brick or tube temperatures.

A further object of my invention is to provide a flat arch that can be assembled completely before being put in place in the furnace for, if the arch fails in any way the defective arch can be readily removed by disconnecting the two pipe fittings and lifting the complete arch from the T rails. A new arch may be then set in place, the two pipe connections made, loose sand put in place and the boiler is again ready for operation.

A further object of my invention is to provide a superheated steam cooled flat arch which will allow a higher temperature in the furnace due to the furnace being cooled below the dangerous temperature of fire brick and tubes, by using steam. It is of course understood that my invention can be used for either water, steam or vapor that is used to develop power for the power house.

It is further understood that my invention above described in the several different types of boilers can also be cooled by steam if desired.

Tubes 100 are equipped with standard pipe T's 110 on each end having plugs 108 screwed in place so as to provide a way to clean and inspect arch tubes 100. T's 110 have vertical pipes

112 connected thereto and extending upwardly and into steam headers 98 and 102 so as to allow for any expansion of tubes 100 for these vertical tubes 112 will spring slightly without injury.

A further object of my invention is to provide blocks made of fire clay or other suitable refractory material that can be removed without disturbing the rest of the furnace wall. Figures 15, 16, and 17 show a block or fire brick 14 that is U shaped having slot 21 formed to allow the 10 brick to be put in place on the tube. Formed in each brick at the opposite ends thereof are pairs of curved indentations 107. 17 designates pipe clips which fit closely within the indentations 107 and retain the brick on to the tubes 15 in any position. Brick 14 are put in place on the tubes, clips 17 are then put in place on the tubes as indicated in dotted lines on Fig. 15 so that the circular indentations 107 register in a direction circumferentially of the tubes with clips 20 17 and then the clips are rotated into the circular indentations and because the distance between the upper portions of a pair of oppositely disposed clips 17 is less than the diameter of the tube the brick may not move downwardly with 25 respect to said tube while the clips are in place. U shaped brick 14 also permits me to either expose the tubes to the direct action of the flames or else interpose a thin fire brick wall to provide an insulator or else keep one tube cooler 30 than the other. A very important point when it is desired to insure boiler circulation. The clips 107 are arranged in position one at a time, the first clip being located in the dotted line position shown in Fig. 15 and being rotated into one of 35 the indentations before the second clip is arranged in position in a like manner.

Figs. 18 and 19 show pipe hangers 109 shaped to fit the tube at one end and the other forming a jaw 110 for any suitable support. Pipe hangers 40 are clamped together securely on the tubes by bolts 111. The pipe clamps also act as clips to retain the brick to the tubes so that by substituting the pipe clamps for a pair of clips I maintain a tight wall at this point. 45

I claim—

1. A furnace comprising an intermediate support, wall portions suspended from said intermediate support, wall portions supported by said intermediate support above same, and fluid conductors arranged in said walls to prevent overheating thereof, said fluid conductors constituting the sole connection between said walls and said intermediate support. 50

2. A furnace comprising a drum forming a part 55 of the circulatory system of the furnace, tubes arranged in communication with the interior of said drum and extended upwardly therefrom, tubes arranged in communication with the interior of said drum and suspended therefrom, the 60 first-mentioned tubes and the second-mentioned tubes being parts of the circulatory system of the furnace, and refractory members arranged to produce the walls of the furnace, said refractory members being provided with openings formed 65 therethrough through which said tubes extend, and said tubes constituting the sole connection between said walls and said drum.

3. A furnace comprising a wall composed of tubes and refractory members supported by said 70 tubes, each of said refractory members being integrally formed and of approximately U-shaped construction to permit same to be moved onto and off of the associated tube by being moved laterally with respect thereto, and arcuate clips for 75

retaining said refractory members in place on said tubes, said refractory members being provided with arcuate depressions in which said clips are located in a manner to contact firmly with the 5 faces of said tubes and the walls of said arcuate depressions.

4. A boiler furnace having a combustion chamber, a row of spaced metallic tubes arranged along a wall of the chamber so that a fluid flowing through them absorbs heat transmitted through the tube walls from burning fuel in the furnace, a row of preformed refractory blocks carried wholly by each tube along its furnace side and separate clips holding each of said blocks 10 tied to the tubes so that each of the blocks can be separately released and replaced.

5. A boiler furnace having a combustion chamber, a row of spaced metallic tubes arranged along a wall of the chamber so that a fluid flowing through them absorbs heat transmitted through 15

the tube walls from burning fuel in the furnace, a row of preformed refractory blocks carried wholly by each tube along its furnace side, said blocks having recesses and separate clips entering said recesses and holding each of said blocks tied to the tubes so that each of the blocks can be 5 separately released and replaced.

6. A boiler furnace comprising a wall composed of elongated upright tubes forming part of the circulatory system and refractory members supported by the tubes at the lower ends of the latter and free to expand upward with respect to said tubes, said refractory members being approximately U-shaped with the open side inward on some of said tubes and the closed side inward 10 on others, to provide an upward flow in the exposed tubes and a downward flow in those covered by the refractory. 15

CHARLES B. YODER. 20
